CENTRALIZED TRAFFIC CONTROLLING SYSTEM

Application filed January 24, 1931. Serial No. 511,046.

This invention relates to centralized traffic controlling systems, and more particularly to a system of this type when applied to a single track railroad signalled to facilitate both directions of train movement.

Single track railroads are usually equipped with signalling systems of the absolute-permissive-block type, in which trains may move in only one direction in a single track section at one time, and where following trains are protected by signalling indications of clear, caution and stop, depending on the extent of unoccupied track ahead, the same as in double track signalling where trains can move in one direction only and where a danger signal indicates the entrance into an occupied block, the passage of a caution signal indicates the entrance into a block in the rear of an occupied block, and the passage of a clear signal manifests at least two unoccupied blocks in advance of such signal. In other words, absolute-permissive-block or A. P. B. systems prevent the entrance of all opposing trains and permit the movement of following trains

with the usual train spacing. In absolute-permissive-block signalling systems of the superimposed manual control type the starting signals as well as the entering signals located at each end of each single track section have superimposed thereon manual control, so that these signals may be held at stop through suitable control mechanism controlled from a central office. A system of this type has been shown in the prior application of S. N. Wight, Ser. No. 48,553, filed August 6, 1925. Absolute-permissive-block signalling systems usually include two tumble-down circuits, one for each direction of traffic, through the medium of which the home-and-distant relay for each signal of a single track section is controlled by the home-and-distant relay of the signal next in advance, these tumble-down circuits usually use a common return wire.

In view of the above and other important considerations it is proposed in accordance with the present invention to check each link-circuit, so to speak, of a tumble-down circuit for one direction of traffic by including in it the back contacts of two home-and-distant

relays in tumble-down link-circuits for the other direction of traffic, from which it is apparent that the link-circuit of one tumble-down circuit for one direction of traffic only can be energized at a time. With the employment of this cross check or interlock between the tumble-down circuits it is apparent that the direction of traffic cannot readily be set up by the approaching trains themselves, as is done in the usual A. P. B. system, and that it is necessary to determine which of the two tumble-down circuits shall be permitted to be energized through the medium of manually controlled control relays located at the ends of the single track section. Another feature of the present invention resides in an interlock between the starting signals for one direction of traffic and the tumble-down circuits for governing traffic in the opposite direction.

Other objects, purposes and characteristic features of the invention will in part be pointed out hereinafter and will in part be obvious from the drawings.

In describing the invention in detail reference will be made to Figs 1A and 1B, which if laid end to end constitute a drawing which shows the invention applied to a single track section connecting the ends of diverging routes or passing sidings.

Referring to the drawings the track rails I of the main track, including the single track section O, and passing sidings PS¹ and PS² have been shown divided into blocks by insulating joints J to provide the usual track circuits and detector track circuits. At the left hand end or west end of the single track section O is shown a switch S¹ for governing the movement of traffic between the passing siding PS¹ and the single track section O, and at the east end of the single track section O is shown a track switch S² for connecting this single track section to the passing siding PS². With the track switch S¹ are associated a main starting signal 2 and a dwarf starting signal 2^d for governing, respectively, movement of trains off of the main track and off of the side track of the passing siding PS¹ into the single track section O, and similarly has associated there-

with the entering signal 1 and the take-siding signal 1^a for governing the movement of trains off of the single track section O into the main track and the side track of the passing siding PS¹. Similarly, the track switch S² has associated therewith starting signals 7 and 7^a, an entering signal 8 and a take-siding signal 8^a.

The detector track circuit associated with the switch S¹ includes a track relay DT¹ and a battery 11, the track circuit in advance of the signal 2 includes the track relay 2T and the track battery 12, the track circuit in the advance of the signal 3 includes the track relay 3T and a track battery 13, the track circuit in advance of the signal 4 includes the track relay 4T and a track battery 14, the track circuit in advance of the signal 5 includes a track relay 5T and a track battery 15, the track circuit in advance of the signal 6 includes a track relay 6T and a track battery 16, the track circuit in advance of the signal 7 includes the track relay 7T and a track battery 17, and the detector track circuit associated with the switch S² includes a track relay DT² and a track battery 18.

Attention is directed to the fact that each of these starting signals 2, 2^a, 7 and 7^a and the entering signals 1, 1^a, 8 and 8^a are stop-and-stay signals as conventionally indicated by the rectangular signal blades, and that the intermediate signals 3, 4, 5 and 6 are permissive signals as conventionally indicated by the pointed blade, it being, of course, understood that the present invention is not limited to signals of the semaphore type, and that multiple aspect color light signals or color light signals of the movable spectacle type may be used, if desired, in which color light signals or other signal characteristics are used to distinguish the stop-and-stay signals from the permissive signals.

Each signal has been shown controlled by an associated home-and-distant relay HD having a prefix number corresponding to the reference number of the signal, this control has been shown conventionally by dotted lines, and may, if desired, be the same as shown in the prior application of S. N. Wight, Ser. No. 48,553 above referred to, or if light signals are used may be the same as shown in the application of S. N. Wight, Ser. No. 120,423 filed July 3, 1926. Similarly, there is associated with each signal a directional stick relay, such directional stick relay, having, however, not been shown for the signals 1, 2, 7 and 8, which directional stick relays are controlled in the usual way, for instance, as illustrated in the prior applications above referred to.

At the west end of the single track section has been shown a control relay 2ZE which may be controlled from the central office DO in any suitable way as for instance by the lever L¹ through the medium of the line

wire 20 and the contact 21, the control relay 1ZW used for governing the movement of trains from the single track section O into the passing siding PS¹ being controlled by the lever L¹ through the medium of the wire 22. Similarly, the west bound control relay 7ZW is controlled by the lever L² through the medium of line wire 23 and contact 24 of this lever L² and the east bound control relay 8ZE is controlled through this same lever L² and the line wire 25.

Having now pointed out the essential elements of a single track section of railway track through which trains may move in opposite directions, it is believed expedient to consider the operation of the system, that is, the movement of trains from one passing siding to the next passing siding and observing how such direction of train movement may be changed by the operator, at will.

Operation

Let us first note that the signal 4 is the only signal that indicates clear, the signal 6 is the only one that indicates caution and that the remaining signals all assume the stop position. The signal 4 indicates proceed, because the tumble-down circuit for moving traffic from west to east is intact, and the signal 6 indicates caution because although east bound direction of traffic has been set up, the next signal in advance, namely the signal 8, is manually held at stop through the medium of the relay 8ZE, which relay is in its left hand normal stop position.

The home-and-distant relay 6HD is energized to its left hand position, permitting the signal 6 to assume the caution position through the following circuit:—beginning at the terminal (—) of a suitable split battery, contact 30 of the signal 8 assuming its stop position, wire 31, contact 32 of the relays 7ZW assuming its right hand position, wire 33, back contact 34 of the home-and-distant relay 7HD, wire 35, contact 36 of the signals 7^a assuming the stop position, wire 37, contact 38 of the signal 7 assuming its stop position, wire 38^a, front contact 39 of the track relay DT², wire 40, front contact 41 of the relay 7T, wire 42, front contact 43 of the relay 6T, wire 44, back contact 45 of the directional stick relay 5S, wire 46, back contact 47 of the relay 5HD, wire 48, winding of the relay 6HD, to the common return wire C connected to the midpoint of said split battery.

Similarly, the relay 4HD is energized under the assumed conditions through the following circuit:—beginning at the terminal (+) of a suitable split battery, front contact 50 of the relay 6HD, elements 51, 52, 53, 54, 55, 56, 57, 58, 59, 60, 61, 62 and 63, winding of the relay 4HD, to a common return wire C connected to a midpoint of said split battery.

Similarly, the relay 2HD is energized through the following circuit:—beginning at the positive terminal of a suitable split battery, front contact 65 of the relay 4HD,

elements 66, 67, 68, 69, 70, 71, 72, 73, 74, 75 and 76, winding of the relay 2HD, to a common return wire C connected to a midpoint of said split battery.

Let us now assume that there is an east bound train standing on the main track of a passing siding PS¹ and that the operator wishes this train to pass into the main track of the passing siding PS². The operator may first clear his entering signal 8, which is accomplished by operating his lever L² to the right, signifying east bound traffic, under which condition the east bound relay 8ZE is energized to its right hand position through the medium of the line wire 25 and causes the signal 8 to be cleared through the following circuit:—beginning at the terminal (+) of a suitable battery, contact 80 of the relay 8ZE, wire 81, contact 162 of the relay DT², wire 163, switchbox contact 82 closed only if the track switch S² assumes its main track position, wire 83, contacts 84 and 85 of the relay 8HD, and suitable wires for controlling the signal 8 to a position corresponding to the polar position of the relay 8HD, and conventionally shown by the dotted line 86. Clearing of the signal 8 will of course allow the signal 6 to assume the clear position by reason of the reversal of polarity applied to the relay 6HD. Similarly, the operator may clear the signal 2 by operating the east bound relay 2ZE to its right hand position in response to movement of the lever L¹ to its right hand position, under which condition the signal 2 is cleared through the following circuit:—beginning at the (+) terminal of a suitable battery, contact 87 of the relay 2ZE, wire 88, switch box contact 89 closed only when the track switch S¹ assumes the main track position, wire 90, contacts 91 and 92 of the relay 2HD and through suitable wires conventionally shown by the dotted line 93.

The train under consideration may thus now respond to the clearing of the signal 2 and pass into the single track section 0. As this train passes the signal 4 it will pick up the stick relay 4S, all is well understood by those familiar with the art of A. P. B. signalling, and will effect dropping of the relay 4HD, so that the relay 2HD is energized by current of negative polarity fed through the front contact 94 of the directional stick relay 4S and the back contact 65 of the relay 4HD, respectively. Similarly, passage of this train by the signal 6 will pick up the directional stick relay 6S and drop the relay 6HD, thereby applying current of negative polarity to the relay 4HD through the front contact 95 of the relay 6S and the back contact 50 of the relay 6HD. Picking up of the relay 4HD will

of course return the signal 2 to its clear position. The train may thus continue its movement into the main track of the passing siding PS².

Let us now assume that there is a west bound train standing on a passing siding PS², and that the operator at the central office DO wishes this train to proceed through the single track section 0 and into the main track of the passing siding PS¹. The operator will first operate his lever L¹ to the left hand position, thereby returning the relay 2ZE to its left hand position. Movement of the lever L¹ to its left hand position will effect operation of the relay 1ZW to its left hand position. Operation of the relay 2ZE to its left hand position closes the energizing circuit for the relay 3HD at the contact 100 of this relay 2ZE, but this will be of no avail since this circuit is open at numerous other points, such for instance as at back contacts of the home relays 2HD and 4HD. Operation of the relay 1ZW to its left hand position will close the energizing circuit for the signal 1 which may be traced as follows:—beginning at the terminal (+) of a suitable battery, contacts 101 of the relay 1ZW assuming its left hand position, wire 102, contact 98 of the detector track relay DT¹, wire 99, switch box contact 103 closed only if the track switch S¹ is in its main track position, wire 155, contacts 156 and 157 of the relay 1HD, through suitable circuits conventionally shown by the dotted line 158 to the signal 1. This signal 1 is of course controlled in accordance with traffic conditions, in advance, or toward the left of this signal 1 through the medium of the relay 1HD.

The operator will next operate his lever L² to its left position thereby returning the control relay 8ZE to its left hand position and operating the control relay 7ZW to its left hand position, in which position the tumble-down link circuit for the relay 6HD is broken at the contact 32, and in which position of relay 7ZW the circuit for controlling the starting signal 7 at one point, namely at the contact 160 of the relay 7ZW, will be closed. The signal 7 will, however, not clear because the relay 7HD is still deenergized. Opening of the contact 32 of the relay 7ZW will, however, break the energizing circuit for the relay 6HD, which in turn through its contact 50 will break the energizing circuit for the relay 4HD, and which relay 4HD through its contact 65 will break the energizing circuit for the relay 2HD. In other words, the west to east tumble-down circuit will be caused to tumble down, and as soon as the relay 4HD reaches its deenergized position, the east-to-west tumble-down circuit will begin to tumble up, so to speak, this by closure of the energizing circuit for the relay 3HD, which may be traced as follows:—beginning at the terminal (+) of a suitable split battery, contact 104 of the signal 1 assuming its clear position,

wire 105, contact 100 of the relay 2ZE, wire 106, back contact 107 of the relay 2HD, wire 108, front contact 109 of the detector track relay DT¹, contact 110 of the signal 2 closed only when the signal 2 is in the stop position, wire 111, contact 112 of the dwarf signal 2^a assuming its stop position, wire 113, contact 114 of the relay 2T, wire 115, contact 116 of the relay 3T, wire 117, back contact 118 of the relay 4HD, wire 119, back contact 120 of the relay 4S, wire 121, winding of the relay 3HD to the midpoint C of said split battery.

Picking up of the relay 3HD will close the energizing circuit for the relay 5HD which may be traced as follows:—beginning at the terminal (+) of a suitable split battery, front contact 122 of the relay 3HD, elements 123, 124, 125, 126, 127, 128, 129, 130, 131, 132, 133, 134 and 134^a, winding of the relay 5HD to the midpoint C of said split battery. Similarly, picking up of the relay 5HD closes the following energizing circuit for the relay 7HD:—beginning at the terminal (+) of a suitable split battery, contact 135 of the relay 5HD, elements 136, 144, 145, 146, 147, 137, 138, 139, 140, 141, and 142, winding of the relay 7HD, to the midpoint C of said split battery. Picking up of the relay 7HD will permit clearing of the signal 7 through the following circuit:—beginning at the terminal (+) of a suitable battery, contact 160 of the relay 7ZW assuming its left hand position, wire 161, switch box contact 164 closed only when the track switch S² assumes its main track position, wire 165, contacts 166 and 167 of the relay 7HD, through suitable wiring conventionally shown by the dotted line 168, through the signal mechanism of the signal 7 to the other terminal of said battery.

The west bound train occupying the main track of the passing siding PS², may thus in response to the clearing of signal 7 proceed into the single track section O, and will upon each passage of a signal place that signal in a stop position and allow the next signal in the rear to move from the stop to the caution position, all through the medium of home-and-distant relays and directional stick relays as readily understood from the circuits as heretofore traced, so that this train will eventually pass into the main track of the passing siding PS¹.

Attention is directed to the fact that each home-and-distant relay HD can only be energized if the associated home relay for the opposite direction of traffic is deenergized and the opposing relay at the next signal location in advance is deenergized, so that it is absolutely impossible to set up clear signals for both directions of traffic, this irrespective of the condition of the directional stick relays. Also, it will be noted, that in order to change the direction of traffic set up, the operator must first cause the opposing tumble-down circuit to tumble down and

after this has happened he may cause the other tumble-down-circuit to tumble up, so to speak.

Although no particular means has been shown for operating the track switches S¹ and S², these track switches are preferably operated by a switch machine controlled from the central office DO in any suitable manner, which features have for convenience been omitted. It is of course understood that suitable means could be provided for indicating to the train crew when this switch is to be operated in the event the switch is to be operated by hand. Assuming that the switch S¹ may be operated to either of its two positions in response to the operation of a control relay controlled from the dispatcher's office DO, it is apparent that the contact 101 of the relay 1ZW assuming its left hand position will select the take-siding signal 1^a, through the medium of the wire 150 and the switch box contact 103 assuming the take-siding position, instead of selecting the signal 1. Similarly, if the track switch S² assumes the reverse position, operation of the control relay 8ZE to its right hand position will effect clearing of the take-siding signal 8^a, through the medium of the wire 151 and the switch box contact 82 assuming the take-siding position, instead of selecting the signal 8.

Applicants have thus provided an absolute-permissive block signalling system in which very through checking or interlocking between opposing tumble-down-circuits is carried out, and in which the operator must manually set up the desired direction of traffic movement.

Having thus shown and described one rather specific embodiment of our invention, it is desired to be understood that the particular embodiment selected has been selected for the purpose of disclosing the underlying principles and features of safety of the system rather than showing the exact construction preferably employed in practicing the invention or illustrating the scope of the invention, and it is further desired to be understood that suitable additions and modifications may be made to adapt the invention to the particular track lay-out to which the invention is to be applied all without departing from the spirit of the invention or its scope, except as demanded by the scope of the following claims.

What we claim as new is:—

1. In a signalling system for single track railroads, the combination with a single track section connecting two double track sections, of signals for governing traffic in one direction and signals for governing traffic in the other direction through said section, a relay for controlling each signal included in a circuit including a front contact of the relay for the next signal in advance and including a

back contact of the relay for an adjacent signal governing traffic in the opposite direction, and manually controllable means for permitting relays controlling signals for governing traffic in one of said directions to be held at stop.

2. In a signalling system for single track railroads, the combination with a single track section connecting two double track sections, of signals for governing traffic in one direction and signals for governing traffic in the other direction through said section, a relay for each signal, a tumble-down circuit for each direction of traffic comprising a plurality of link-circuits each link-circuit of which includes one of said relays and is controlled by the relay of the next link-circuit in advance, and means for interlocking each link of one tumble-down circuit with one link of the other tumble-down circuit in such manner that if one tumble-down circuit is energized all the links of the other tumble-down circuit are de-energized.

3. In a signalling system for single track railroads, the combination with a single track section connecting two double track sections, of signals for governing traffic in one direction and signals for governing traffic in the other direction through said section, a relay for each signal, a tumble-down circuit for each direction of traffic each comprising successive link-circuits one for each relay and each link-circuit controlled by the next link circuit in advance, and means for interlocking individually the link-circuits of said tumble-down circuits.

4. In a signalling system for single track railroads, the combination with a single track section connecting two double track sections, of signals for governing traffic in one direction and signals for governing traffic in the other direction through said section, a relay for each signal, a tumble-down circuit for each direction of traffic each comprising successive link-circuits one for each relay and each link-circuit controlled by the next link circuit in advance, means for interlocking the link-circuits individually of said tumble-down circuits, and means for manually controlling said tumble-down circuits.

5. In a signalling system for single track railroads, the combination with a single track section connecting two double track sections, of signals for governing traffic in one direction and signals for governing traffic in the other direction through said section, a relay for each signal, a tumble-down circuit for each direction of traffic each comprising successive link-circuits one for each relay and each link-circuit controlled by the next link circuit in advance, and a back contact of the relay for one link circuit included in the adjacent link-circuit for the opposite direction of traffic.

6. In a signalling system for single track

railroads, the combination with a single track section connecting two double track sections, of signals for governing traffic in one direction and signals for governing traffic in the other direction through said section, a relay for each signal, a tumble-down circuit for each direction of traffic each comprising successive link-circuits one for each relay and each link-circuit controlled by the next link circuit in advance, and means for interlocking the link-circuit for one direction of traffic with the adjacent link-circuit for the opposite direction of traffic.

7. In a signalling system for single track railroads, the combination with a single track section connecting two double track sections, of signals for governing traffic in one direction and signals for governing traffic in the other direction through said section, a relay for each signal, a tumble-down circuit for each direction of traffic each comprising successive link-circuits one for each relay and each link-circuit controlled by the next link circuit in advance, means for interlocking the link-circuit for one direction of traffic with the adjacent link-circuit for the opposite direction of traffic, and other means for interlocking said tumble-down circuits.

In testimony whereof we hereby affix our signatures.
